DESIGN FOR A SHOE OR SIMILAR ARTICLE

David Levin, New York, N. Y., assignor to Newton Elkin Shoe Company, Philadelphia, Pa., a corporation of Pennsylvania

Application September 11, 1939, Serial No. 87,129

Term of patent 3½ years

To all whom it may concern:

Be it known that I, David Levin, a citizen of the United States, residing in New York city, in the county of New York and in the State of New York, have invented a new, original, and ornamental Design for a Shoe or Similar Article, of which the following is a specification, reference being had to the accompanying drawing, forming part thereof.

I claim:

The ornamental design for a shoe or similar article, substantially as shown.

DAVID LEVIN.
